ATTACHMENT FOR LIFT TRUCKS

Carl B. Marietta, Battle Creek, Mich., assignor to
 Clark Equipment Company, Buchanan, Mich.,
 a corporation of Michigan

Application October 21, 1949, Serial No. 122,763

2 Claims. (Cl. 214—655)

1

This invention relates to an attachment for lift trucks but, more particularly, is directed to an attachment provided for use on the forks of the lift truck in gripping rounded objects such as barrels, drums, or the like, for the purpose of transporting, stacking, or tiering the same.

Primarily, the present invention contemplates taking a lift truck of the type using the standard L-shaped lift fork elements and attaching to such fork elements suitable mechanism whereby one or more cylindrical objects may be grasped therebetween, lifted and stacked, or transported. In connection with this operation, it is necessary that the lift fork elements be so mounted upon the fork truck that they can be moved laterally toward and away from each other to provide the necessary gripping action.

Other objects and advantages of the present invention will appear more fully from the following detailed description which, taken in conjunction with the accompanying drawings, will disclose to those skilled in the art the particular construction and operation of the present invention.

In the drawings,

Figure 1 is a side elevational view of a fork truck embodying the present invention.

Figure 2 is a top plan view, partly diagrammatic, showing the lift fork mechanism and the adapting members.

Figure 3 is an isometric view of the construction shown in Figures 1 and 2 insofar as the clamp and fork arrangement is concerned.

Figure 4 is a sectional view taken substantially on line 4—4 of Figure 3.

Figure 5 is a sectional view taken substantially on line 5—5 of Figure 3; and

Figure 6 is a sectional view taken substantially on line 6—6 of Figure 3.

Referring now in detail to the drawings, an industrial truck is indicated generally at 5, including the drive wheels 6, the steering wheels 7, and the vertical mast or upright assembly 8 upon which is mounted a load supporting carriage 9, guided and arranged for vertical movement within the mast 8 in any conventional or well-known manner.

The carriage 9 includes a box-like structure, shown in more detail in Figure 3, having a back- ing plate portion 10 and suitable guideways formed therein for receiving slidable members 12 and 13 mounted at the upper and lower ends of vertically extending members 14, which mem- bers are adapted to have secured to the forward faces thereof the lift fork elements 15 as by means

5 of cap screws, bolts, or the like. The forwardly projecting finger portions 16 of the lift forks are of conventional design and, in normal operation, are adapted to be disposed underneath a load for picking the same up and transporting it.

There is a forward plate 17 mounted upon the assembly 9 for closing the guideways within which the guides 12 and 13 slide and which also forms a closure confining therebetween the clamp cylinders 18 and 19 which are mounted in opposed relationship and have piston rods 20 and 22 connected respectively with the vehicle members 14, whereby upon introduction of fluid under pressure into the cylinders, the piston rods tend to move the members 14 toward or away from each other, thereby moving the fork portions 16 toward or away from each other. This clamping mechanism is only one of a number of well-known ways in which to provide a gripping action between the fork members and need not be described in any further detail.

As shown in detail in Figures 2 and 3 and the sectional views of Figures 4, 5 and 6, each of the fork portions 16 is adapted to receive channel-shaped members 25, which members have the web portions 26 thereof in facing relation on the inner longitudinal edges of the finger portions 16 of the forks. The channel sections of the members 25 overlie and embrace the finger portions of the forks and are adapted to be pivotally mounted or hinged thereto by means of the pivot pins 27, shown more in detail in Figure 6, these pins having the head portion on one of the flanges of the channel-shaped members 25 and being threaded into the lower flange portion thereof, with the bushings 28 forming a bearing for the pivotal connection.

Preferably a suitable spacer member 29 is provided for limiting relative vertical movement between the fork 16 and the members 25.

Adjacent the forward and rear ends of the members 25, there are provided additional spacing members 30, as shown in Figure 4, which serve as pilots or friction reducing elements to accommodate relative swinging movement of the members 25 within a limited range with respect to the fork portions 16.

Immediately to the rear of the pivots 27, which are substantially centrally located intermediate the ends of the members 25, there is provided spring means, indicated at 30 in Figure 5, biased between a recessed portion of the fork 16 and web 26 of the members 25, normally urging the rear portions of the members 25 toward each other or inwardly with respect to the space be-

tween the forks. This, due to the hinging action provided by the pins 27, moves the forwardly projecting ends of the members 25 outwardly or away from each other, thereby opening up the space between the forks when no load is to be lifted. This gives additional clearance so that if the fork truck is moved into a position approaching the load, the outer ends of the members 25 will be spaced apart as far as possible to accommodate entry of the load therebetween.

While the present invention is designed primarily for picking up barrels, drums, or the like, it can be used for picking up any cylindrical object, such as rolls of newsprint, paper, roofing material, or the like.

In Figure 2 I have shown two cylindrical drum members diagrammatically at A and B. It will be noted that the web portions of the members 25 are provided with arcuate indentations or recesses 32, disposed in longitudinally spaced facing relationship. These indentations are adapted to receive the peripheral surface of a rounded object, such as the objects A and B, and when the clamp mechanism is actuated to move the forks toward each other, these arcuate indentations will receive the load and clamp the same firmly between the forks. The frictional pressure imposed by this clamping action is sufficient to allow the elevating carriage to then pick up the load and transport it, tier it, or stack it.

Reverse operation of the clamping mechanism will, of course, release the load and allow it to be disposed upon the floor or upon the top of a similar load if it is to be stacked or tiered. The pivotal action provided by the pins 27 is of importance in accommodating the fork member so that the pressure is evenly applied to both of the members A and B by the clamping mechanism, thereby insuring equalized frictional gripping on both of the members. It is of further importance, in combination with the springs 30, to open up the forward ends of the forks as far as possible for entry about the sides of the cylindrical members to be lifted.

I am aware that various changes may be made in the configuration and relative sizes of the members 25 with respect to the forks 16 and in the mounting of the same upon the forks, and I therefore do not intend to be limited except as defined by the scope and spirit of the appended claims.

I claim:

1. In an industrial truck having a pair of forwardly projecting relatively movable lift fork elements and means carried by the truck for moving the fork elements toward and away from each other, means for adapting the fork elements as gripping elements comprising a pair of channel-shaped members embracing respectively the opposed inner longitudinal edges of the fork elements, the said channel-shaped members and the respective lift fork elements being approximately

co-extensive and the said members being pivotally connected about substantially vertical axes located centrally intermediate their ends to the respective fork elements, a plurality of arcuate indentations in the web portions of the said channel-shaped members for gripping cylindrical objects between the said members, each of the said members having at least one such indentation on each side of its said centrally located pivot axis, and a pair of springs positioned respectively between the said inner edges of the fork elements and the reverse surfaces of the said web portions for biasing the forward ends of the said channel-shaped members outwardly away from each other.

5 2. In an industrial lift truck having a pair of forwardly projecting relatively movable lift fork elements and means carried by the truck for moving the fork elements toward and away from each other, means for adapting the fork elements as gripping elements comprising a pair of members of channel-shaped section embracing respectively the opposed inner longitudinal edges of the fork elements, the said channel-shaped members and the respective lift fork elements being approximately co-extensive and the said channel-shaped members being pivotally connected about substantially vertical axes located centrally intermediate their ends to the respective fork elements, a pair of arcuate indentations in the web portions

10 30 of the said channel-shaped members for gripping cylindrical objects between the channel-shaped members, each of the said channel-shaped members having at least one such indentation on each side of its said centrally located vertical pivot axis, and a pair of compression springs positioned respectively between the said inner edges of the fork elements and the reverse surfaces of the said web portions of the channel-shaped members and rearwardly of the said pivot axes for biasing the forward ends of the said channel-shaped members outwardly away from each other.
